UNITED STATES PATENT OFFICE.

JAMES R. MOFFATT AND RALPH S. KELSO, OF CHICAGO, ILLINOIS, ASSIGNEES TO UNION
SPECIAL MACHINE COMPANY, OF CHICAGO, ILLINOIS, A CORPORATION OF ILLINOIS.

SEWING-MACHINE.

1,202,406.

Specification of Letters Patent.

Patented Oct. 24, 1916.

Application filed December 1, 1911. Serial No. 663,302.

To all whom it may concern:

Be it known that we, JAMES R. MOFFATT and RALPH S. KELSO, citizens of the United States, residing at Chicago, in the county 5 of Cook, State of Illinois, have invented certain new and useful Improvements in Sewing-Machines, of which the following is a description, reference being had to the accompanying drawing and to the letters 10 and figures of reference marked thereon.

Our invention relates to an improvement in sewing machines, and particularly to a multiple needle machine of the cylindrical bed plate type, in which a plurality of lines 15 of stitching are formed in the fabric, which is fed longitudinally of the bed plate. In a machine of this character, when a plurality of needles are used, each having a looper coöperating with it, thus making a plurality 20 of independent rows of stitching, the needles are set oblique to each other respecting the line of feed, and the loopers reciprocate transversely of the line of feed. The space 25 is necessarily very much restricted in which the loopers must operate to get the forward and back and sidewise movements, and they must be made to swing within the limits of a very restricted area, since the bed plate must be of as small diameter as possible. 30 The object of the invention, therefore, is to so support the loopers that they shall have the full swing necessary to properly concatenate with the needles to form the independent rows of stitches, but yet at the 35 same time, the movements may take place in a bed plate of minimum diameter.

The invention, therefore, consists in the matters hereinafter described and referred to in the appended claim.

40 The invention is illustrated in the accompanying drawings, in which—

Figure 1 is a side elevation of a sewing machine embodying our invention, partly in section and parts being broken away; Figs. 45 2, 3, 4 and 5 are sectional end views, showing the needles and loopers in different relative positions during their travel; Fig. 6 is a detail top-plan view of the loopers in full and dotted positions, the needles being 50 shown in section; Fig. 7 is a detail view of the needle guard; Fig. 8 is a detail perspective of the end of the looper-supporting shaft; and Figs. 9 and 10 plan and sectional views respectively illustrating the

work done on the machine; Fig. 10 being 55 a section on line 10—10 of Fig. 9.

In these drawings, the machine as a whole is of the well known type known as the Union Special side wheel cylinder machine, and having the cylindrical bed plate 1, the 60 presser foot 2, the needle bar 3, the looper shaft 4, the feed dog 5 reciprocating longitudinally of the bed plate, the needles 6, loopers 7 and folder 8.

The needles 6 are herein shown as three 65 in number, set oblique to one another respecting the line of feed, the left hand one looking toward the machine being in the rear. It will be understood, however, that the reverse arrangement may be used.

The forward end of the looper shaft 4 has an offset flattened projection 9, having three 70 openings 10 in line, in which the shanks of the loopers are set, the loopers being of different lengths, so that their beaks set obliquely to one another respecting the line of feed, corresponding to the set of the needles.

11 represents the needle guard having the three beveled projections for guiding and preventing deflection of the needles.

By having the eccentric offset 9, it is possible to have loopers of different lengths with their shanks all set in line, and to get the full throw of each looper necessary to take its needle loop and perform its other movements, and still have those movements take place in the space of a cylindrical bed plate of small size, and yet without any danger of the needles in their lowest position striking the looper support.

The present construction lends itself readily to the formation of a plurality of independent rows of stitches on a small cylindrical bed plate, without the necessity of having a wide head on the looper shaft to 95 accommodate a series of obliquely set holes for the looper shanks, and without the necessity of cutting out the head of the looper shaft to allow the descent of the needles to their lowest point, and without necessitating 100 the shortening of the movement of the loopers and the needles.

The relative movements of the needles and loopers are shown in Figs. 2 to 6 inclusive. In Fig. 2, the loopers are just starting forward and the needles are starting up; in Fig. 3 the beak of the forward looper is just passing into the loop of the right hand

needle, the other loopers coöperating with their needles similarly. In Fig. 6, the loopers are shown in full lines as having completed their forward movement, and in dotted lines as having moved over in their needle-avoiding movement and coming back. In Figs. 4 and 5, they are going through their backward movements, and the needles are coming down.

Having thus described our invention, what we claim as new and desire to secure by Letters Patent, is:—

The combination with a cylindrical work support, of a needle bar, a plurality of needles carried by said needle bar and arranged in line oblique to the line of feed, a looper supporting shaft arranged with its axis horizontal and in a vertical plane containing the needle bar, said shaft having an

offset head extending in the same general direction as the looper shaft and a plurality of loopers carried thereby having their points arranged in a line substantially parallel with the line of the needles, said offset head being so disposed that when the needles are at the lower end of their stroke and the loopers are retracted, said offset head projects downwardly from the axis of the looper supporting shaft forming a clearance space for the points of the needles.

In testimony whereof we affix our signatures, in presence of two witnesses.

JAMES R. MOFFATT.
RALPH S. KELSO.
